UNITED STATES PATENT OFFICE.

JAMES SHARPE, OF DETROIT, MICHIGAN.

DESIGN FOR A GAME APPARATUS.

55,092.

Specification for Design.

Patented May 4, 1920.

Application filed June 4, 1919. Serial No. 301,855. Term of patent 7 years.

To all whom it may concern:

Be it known that I, JAMES SHARPE, a citizen of the United States, residing at Detroit, in the county of Wayne and State of Michigan, have invented a new, original, and ornamental Design for a Game Apparatus, of which the following is a specification, reference being had to the accompanying drawings, forming a part thereof.

The figure shows a perspective view of the game apparatus showing my new design.

I claim:

The ornamental design for a game apparatus as shown.

JAMES SHARPE.

Witnesses:

MARY KENNEDY,
GLEN SMITH.
